(57) **CLAIM**

The ornamental design for a pet clipper, as shown and described.

DESCRIPTION

FIG. 1 is a front and top perspective view of a pet clipper, showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear and bottom perspective view thereof.

FIG. 9 is an enlarged view of portion 9 shown in FIG. 1.

FIG. 10 is an enlarged view of portion 10 shown in FIG. 1; and,

FIG. 11 is an enlarged view of portion 11 shown in FIG. 8. The broken lines in the drawings depict portions of the pet clipper that form no part of the claimed design. The additional broken lines surrounding the enlargements in FIGS. 1 and 8-11 are for the purpose of annotating the enlarged views only, and form no part of the claimed design.
